CLAIM

The ornamental design for a hydraulic excavator, as shown and described.

DESCRIPTION

FIG. 1 is a perspective view of a hydraulic excavator showing my new design;

FIG. 2 is a front view thereof;

FIG. 3 is a rear view thereof;

FIG. 4 is a left side view thereof;

FIG. 5 is a right side view thereof; and,

FIG. 6 is a top plan view thereof.

The broken lines represent portions of the hydraulic excavator that form no part of the claimed design.
